UNITED STATES PATENT OFFICE.

ARTHUR PONTON, OF MURDOCK, ILLINOIS.

BED-SPRING TIGHTENER.

1,089,007.

Specification of Letters Patent. Patented Mar. 3, 1914.

Application filed March 21, 1912. Serial No. 685,217.

To all whom it may concern:

Be it known that I, ARTHUR PONTON, a citizen of the United States, residing at Murdock, in the county of Douglas, State of Illinois, have invented certain new and useful Improvements in Bed-Spring Tighteners; and I do hereby declare the following to be a full, clear, and exact description of the invention, such as will enable others skilled in the art to which it appertains to make and use the same.

This invention relates to improvements in bed spring tighteners, and more particularly to one for stretching fabric springs.

15 The invention has for its object to provide a stretcher which may be conveniently operated for tightening the springs to restore the same to their normal condition.

With this and other objects in view, the 20 invention consists in certain novel features of construction, combination and arrangement of parts as will be hereinafter fully described and claimed.

In the drawing: Figure 1 is a plan view 25 of the device. Fig. 2 is a side elevation of the same. Fig. 3 is a sectional view on line 3-3 of Fig. 1. Fig. 4 is a top plan view showing the device in one of its stretched 30 positions. Fig. 5 is a bottom plan view of the device. Fig. 6 is a detailed perspective view of one of the rod connecting castings.

Referring to the drawing, the numeral 1 designates the side bars of the frame, said bars being held in spaced parallel relation 35 by metallic straps 2. The ends of the side bars are formed with slots 3 for adjustably supporting the opposite ends of the end bars 4. The wire fabric forming the spring 5 is secured, in any suitable manner to the end 40 bars.

Formed centrally upon the opposite faces of the bars 4 are castings 6, said castings being formed with spaced ears 7 for pivotally receiving the outer ends of the rods 8, the 45 inner ends of said rods being threaded for engagement by the turn-buckle 9. Similar castings 10 are mounted upon the opposing faces of the end bars 4, and upon opposite sides of the castings 6, said castings serving 50 to pivotally connect the outer ends of the brace arms 11 to the end bars. The brace arms have their inner ends formed with angular extensions 12 having perforations 13 formed therein and adapted to register with 55 the perforations 14 formed in the rods 8.

The rods 8 are gradually curved downwardly at their inner ends to accommodate the sagging of the spring 5 near its center due to the fact that the weight of the body is greater at this point upon the mattress 60 and springs than at any other.

It oftentimes occurs that when a person sleeps constantly upon one side of the mattress, that portion of the springs directly thereunder will naturally stretch more, and 65 to overcome this, the brace arms 11 may be so adjusted that one of the perforations 13 therein will register with one of the perforations 14 of the rods 8 and in advance of the angular extension 12 of the oppositely disposed arm 11, and at which time clamping bolts are passed through the registered perforations of the different parts, thus holding 70 the adjusted end bar in diagonal relation to the side bars, as clearly shown in Fig. 4 75 of the drawing.

From this construction, it will be seen that upon manipulation of the turnbuckle 9, the spring 5 will be effectually stretched through the medium of the rods 8 and at a time when 80 the end bars 4 are disposed transversely or diagonally with the side bars 1, and as the occasion may require.

What is claimed is:

A bed spring tightener comprising a pair 85 of side bars having slots formed in their ends, end bars supported in said slots, a fabric spring having its ends secured to the end bars, rods having their outer ends pivotally connected to the end bars, a turn buckle connecting the inner ends of said rods, means for shifting the end bars in diagonal relation to the side bars, said means consisting of a pair of arms pivotally connected at their outer ends to each end bar and having 90 their inner ends adapted to be adjustably connected to said rods, and adapted to have their ends adjustably connected to the opposite sides of said rods and in diagonal relation, thereby stretching one side edge of 100 the spring more than the other upon operation of the turn buckle.

In testimony whereof, I affix my signature, in presence of two witnesses.

ARTHUR PONTON.
